UNITED STATES PATENT OFFICE.

WILLIAM G. BUTLER, OF WILKES-BARRE, PENNSYLVANIA.

ADJUSTABLE SOCKET-WRENCH.

1,140,947.

Specification of Letters Patent.

Patented May 25, 1915.

Application filed August 11, 1914. Serial No. 856,203.

To all whom it may concern:

Be it known that I, WILLIAM G. BUTLER, a citizen of the United States, residing at Wilkes-Barre, in the county of Luzerne and State of Pennsylvania, have invented certain new and useful Improvements in Adjustable Socket-Wrenches; and I do hereby declare the following to be a full, clear, and exact description of the invention, such as will enable others skilled in the art to which it appertains to make and use the same.

My invention relates to wrenches, and more particularly to a wrench which is adapted to use with nuts of various sizes and without the necessity of making adjustments, thus materially reducing the cost of manufacture and at the same time reducing the liability of breakage.

In the accompanying drawings, which form part of this specification; Figure 1 is a longitudinal sectional view of the wrench in one of its operating positions. Fig. 2 is a similar view showing the wrench in another position, and Fig. 3 is an end view.

Reference being had to the drawings and the designating characters thereon, the numeral 1 indicates a tubular member which may be of any desired form in cross-section, and the numeral 2 indicates a second tubular member preferably of the same shape as the tubular member 1, and of a size to permit of its sliding freely therein.

The tubular member 1 has one of its extremities enlarged as at 3, and near said enlarged portion 3, is provided with an opening 5, as shown in Fig. 1 and as shown in Fig. 2, a similar opening 5' is provided diametrically opposite the opening 5. Near the opposite extremity of the tubular member 1, are arranged a plurality of diametrically opposite openings 4 and 4'. The member 1 is also provided with a longitudinal slot 6, the purpose of which will be herein-after set forth.

45 The member 2 which as above stated is freely slidable within the member 1 has one of its extremities reduced as at 7, and near this reduced extremity 7 it is provided with diametrically opposite openings 8 and 8', while near its opposite extremity is provided with diametrically opposite openings 9 and 9'.

To limit the movement of the two members 1 and 2 relatively to each other, a pin 10 is employed, this pin being connected at

11 to the inner face of the tubular member 2 and having its opposite extremity 12 projecting through an opening 13 and into the slot 6, which prevents removal of the inner member 2. A pin 15 is used in connection with the device, said pin being adapted to be used as an operating handle.

When it is desired to use either the enlarged extremity 3 of the member 1 or the reduced extremity 7 of the member 2, the members 1 and 2 are positioned as in Fig. 1 and the operating member 15 either in the openings 5 or 5' of the member 1 or the openings 8 or 8' of the member 2. When it is desired to use the opposite extremities of the members 1 and 2, they are positioned as shown in Fig. 2, and the operating member 15 inserted in the diametrically opposite openings 4 or 4' of the member 1 or the diametrically opposite openings 9 or 9' of the member 2.

It is obvious that changes in the details of construction may be made without departing from the spirit of my invention.

Having thus fully described my invention, what I claim is;

1. In a wrench, the combination with a tubular member provided with a plurality of openings and a longitudinal slot, of a smaller tubular member slidable therein, and provided with a plurality of openings, a pin carried by said second tubular member and projecting in said longitudinal slot, and an operating handle adapted to be passed through the openings in either of the tubular members for engagement with the extremity of the other tubular member to lock the tubular members against relative movement in operative position.

2. In a wrench, the combination with a tubular member provided with a plurality of openings and a longitudinal slot, of a second tubular member slidable within the same and provided with a plurality of openings, a pin carried by the second tubular member and projecting into said longitudinal slot, and an operating handle adapted to be passed through the openings of either of said tubular members when the pin of the inner member contacts either extremity of said longitudinal slot, said operating handle being adapted to engage the adjacent extremity of the tubular member by which it is desired to coact with, and coöperate with said pin and said longitudinal slot to lock

the tubular members against relative movement, when in operative position.

3. In a wrench, the combination with a tubular member provided with a plurality of 5 openings and a longitudinal slot, of a second tubular member slidable therein and provided with a plurality of openings, a pin secured at one end to a wall of said second 10 tubular member and having the other of its ends engaged in said longitudinal slot, and an operating handle adapted to be passed through the openings of either of said mem-

bers whereby the latter are retained against relative movement, said pin contacting the extremity of said longitudinal slot opposite to that end of the same adjacent the openings receiving said operating handle. 15

In testimony whereof I affix my signature, in presence of two witnesses.

WILLIAM G. BUTLER.
